OF SYRACUSE, NEW YORK, A CORPORATION OF NEW YORK

BOOK COVER

Application filed April 4, 1930. Serial No. 441,549.

This invention relates to a new and improved book cover.

In making covers for books which are to be used commercially and thus be subjected to hard usage, it is usual to place a textile covering on the body of the cover on the outside and then to protect the outer corners of the cover with a protective covering of, as for instance, leather.

10. These protective coverings for the corners of the cover are usually secured in place by means of some adhesive, and being affixed to the upper surface of the textile covering, they will extend upwardly their own thickness from such textile material.

When protective coverings are put on in this way, there is a great liability, and it frequently happens, that the protective covering during use will be loosened from the textile material due to the fact that such protective covering extends upwardly from the textile material and presents an edge on which the fingers of the user will frequently catch.

20. The main object of my invention is to provide a cover which will have the protective covering assembled on the textile material in such a way that it will present no exposed edge with the result that there is no liability of the protective covering becoming loosened during use.

Other objects and advantages relate to size, shape and arrangement of parts and the method of assembling the same, all as will 30 more fully appear from the following description taken in connection with the accompanying drawings in which:—

Figure 1 is a perspective view of a book having my improved cover.

20. Figure 2 is a section on line 2—2 of Figure 1.

Figure 3 is a fragmentary perspective view of one corner of a cover without the protective covering for such corner.

40. It will be understood that the type of book with which my covers are to be used is immaterial, but for the purpose of describing my invention, I have here shown a book which is usually known as a prong loose leaf binder in which is provided opposed back members

1 and 2 hinged together and each being provided with a plurality of opposed prongs 3.

To one longitudinal edge of back member 1 is hinged a cover 4 and a similar cover 5 is hinged to one longitudinal edge of the other back member 2.

Covers 4 and 5 are similarly made and for the purpose of explaining my invention, I will describe only one cover 4.

Cover 4 has its main body formed preferably from bookbinder's board, although other material may be used if desired.

A main covering 7, preferably of textile material, although other materials may be used, is adhesively secured to the upper surface of the bookbinder's board 6 and has its edges turned down and under to extend a short distance inwardly on the under surface of cover 4.

I then form adjacent each outer corner of cover 4 a groove 8 which extends from the outer edge of cover 4 to the front edge of cover 4. The position of groove 8 in relation to the corners of the cover 4 may be varied as desired depending upon the shape and size it is desired to have the protective covering which is about to be described.

For the sake of uniformity and attractiveness of appearance, I prefer to so locate groove 8 that it, with the two sides of the adjacent corner of the book, will form approximately an isosceles triangle.

I then form from leather or other appropriate material, a triangle-shaped protective covering 9 which is provided on its under surface with an adhesive. One edge of covering 9 is then positioned in groove 8, groove 8 being of a sufficient depth so that the edge of covering 9 will be beneath the upper surface of the covering 7.

The protective covering 9 is then placed in position on the outer corner of cover 4 and is bent downwardly and inwardly so that it extends a short distance on the undersurface of cover 4. I then adhesively secure to the under surface of cover 4, a covering 10 usually of paper which has its edges overlying the inwardly extending edges of coverings 7 and 9.

It will be understood that I provide grooves 8 and protective coverings 9 for the two outer corners of both covers 4 and 5.

Although I have here shown and described 5 a cover and protective coverings for the corners thereof of a particular shape and size, it will be understood that the shapes and sizes of covers and protective coverings for the corners and the location of the grooves 8 10 in relation to the corners of the covers may be varied as may be the material from which the various parts are made, for although I have shown and described a specific structure and form of part as an embodiment of an 15 amplification of my invention, I do not desire to restrict myself to the exact size, shape or relation of parts as various changes may be made within the scope of the appended claim.

20 I claim:

25 A book cover comprising a body portion having a groove in the outer side thereof extending diagonally from a longitudinal edge of the body portion to an outer end thereof so as to define a substantially triangular portion 30 at the corner of the body portion and a protective covering of leather secured to the body portion having its inner edge seated in the groove and lying below the outer surface 35 of the body portion and having its other edges extending around the longitudinal edge of the body portion and the outer end of the same, as defined by said groove.

40 In witness whereof I have hereunto set my hand this 28 day of March, 1930.

FLOYD G. BOLTON.
